UNITED STATES PATENT OFFICE

VICTOR HUGHES, OF DETROIT, MICHIGAN, ASSIGNOR TO GENERAL MOTORS RESEARCH CORPORATION, OF DETROIT, MICHIGAN, A CORPORATION OF DELAWARE

COMPOSITE PISTON

Application filed March 1, 1928. Serial No. 258,424.

This invention relates to internal combustion engines and more particularly to an improvement in pistons which are adapted to reciprocate within the engine cylinders.

It is one of the objects of the invention to provide a piston of composite formation, which will be simple in construction and of low cost, and which will have the combined advantages of freedom from strains, long wear, 10 light weight and rapid heat dissipation.

Various other objects and advantages will be apparent from the following description taken in connection with the accompanying drawing wherein Figure 1 is a vertical sectional view of the piston embodying the present invention and is taken on line 1—1 of Figure 2. Figure 2 is a similar sectional view taken at right angles to that of Figure 1, as on line 2—2 in Figure 1. Figure 3 is a 20 transverse sectional view on line 3—3 of Figure 1. Figure 4 is a transverse sectional view on line 4—4 of Figure 2, and Figure 5 is a detail section illustrating the connection between two of the piston parts.

Referring by reference characters to the accompanying drawing, the numerals 1—1 indicate a pair of arcuate flexible sections preferably formed from sheet metal, each having a pair of lateral extensions or side portions 3, terminating in out-turned flanges or angular end portions 4. Cast onto the end portions 4 are a pair of spaced piston pin bosses 5—5, depending from and forming an integral part of the piston head 6, having the 35 usual ring grooves 7, and which consists of aluminum or other similar light weight metal having a relatively high coefficient of expansion. Surrounding the bosses and arcuate sections 1 is a tubular sleeve or cylindrical skirt 8, formed from sheet steel or other ferrous metal, and which is carried by the arcuate section, being welded or otherwise secured thereto at substantially diametrically opposite points spaced 90° from the axis of the 45 piston pin bosses.

To facilitate the union of the arcuate portions and skirt, two rows of bosses or teats 9 may be provided in the arcuate section, which are spot welded to the skirt.

From the above description, it will be seen

that the explosion forces are received by the aluminum head and transmitted directly through the dependent pin bosses to the connecting rod, the skirt 8 being entirely relieved thereof, and serving the sole purpose of a 55 guide or contact surface. Because of the low coefficient of expansion of the steel skirt, the clearance to be provided between the walls of the cylinder and piston may be made quite small or comparable with that of an all iron 60 piston, thereby insuring a close fit and eliminating piston slap. The aluminum head makes for light weight, reduces the inertia of the piston and results in rapid heat dissipation, allowing the skirt to remain comparatively cool. The difference in the rate of 65 expansion of the head and skirt is compensated for by the flexing or distortion of the arcuate sections, without the imposition of strains on either the skirt or head.

While the invention has been described in but one specific embodiment, it is to be understood that various modifications may be made, such as come within the scope of the appended claims.

Having thus described my invention, I claim:

1. A composite piston, including a shell of ferrous metal, an aluminum head therefor, having dependent piston pin bosses, and an 80 inherently resilient tubular body carried by said bosses and to which said shell is attached.

2. A piston, including a tubular skirt having a relatively low co-efficient of expansion 85 a head having a relatively high co-efficient of expansion and being provided with integral dependent piston pin bosses extending within the skirt, and a separately formed resilient tubular body carried by said bosses and secured to the skirt at substantially 90° from the bosses.

3. A composite piston, including a skirt having a relatively low coefficient of expansion, a head therefor having a relatively high 95 coefficient of expansion, and provided with integral dependent piston pin bosses extending within said skirt, and a pair of resilient arcuate elements secured to the skirt at substantially diametrically opposite points, each 100

of said elements having lateral portions secured to the piston pin bosses.

4. A composite piston, including a cast metal head having a relatively high coefficient of expansion and provided with a pair of dependent piston pin bosses, a pair of resilient arcuate sections each having a pair of lateral extensions provided with flanged extremities embedded within the respective 10 bosses, and a skirt having a relatively low coefficient of expansion surrounding said bosses and secured to said arcuate sections at substantially diametrically opposite points, 90° from the axis of said piston pin bosses.
- 15 5. A piston including a tubular skirt, a head therefor separate from the skirt and provided with integral piston pin bosses that extend into the skirt, and a pair of resilient tie members of U shape in cross section, each 20 having a portion thereof united with the skirt and having the legs thereof imbedded in the respective bosses.

In testimony whereof I affix my signature.
VICTOR HUGHES.
